CLAIM

The ornamental design for a female unit for quick-release buckle, as shown.

DESCRIPTION

FIG. 1 is a perspective view of a female unit for a quick-release buckle in accordance with one embodiment of the design;

FIG. 2 is a top view thereof;

FIG. 3 is a front view thereof;

FIG. 4 is a left side view thereof;

FIG. 5 is a right side view thereof;

FIG. 6 is a bottom view thereof;

FIG. 7 is a back view thereof;

FIG. 8 is a perspective view of a female unit for a quick-release buckle showing a second embodiment of my new design;

FIG. 9 is a top view of FIG. 8;

FIG. 10 is a front view of FIG. 8;

FIG. 11 is a left side view of FIG. 8;

FIG. 12 is a right side view of FIG. 8;

FIG. 13 is a bottom view of FIG. 8; and,

FIG. 14 is a back view of FIG. 8.
